Primary Examiner — Jeffrey D Asch*Assistant Examiner* — Caitlin A Laverty(74) Attorney, Agent, or Firm — Kristin D. Wheeler(57) CLAIM

The ornamental design for a golf bag, as shown and described.

DESCRIPTION

FIG. 1 is a perspective view of a golf bag of this invention including side pockets;

FIG. 2 is a first side view of a golf bag of this invention including side pockets;

FIG. 3 is a front view of a golf bag of this invention including side pockets;

FIG. 4 is a second side view of a golf bag of this invention including side pockets;

FIG. 5 is a rear view of a golf bag of this invention including side pockets;

FIG. 6 is a top plan view of a golf bag of this invention including side pockets; and,

FIG. 7 is a bottom plan view of a golf bag of this invention including side pockets.

In FIGS. 1-7, the lighter broken lines showing portions of the golf bag are for purposes of illustrating environment and form no part of the claimed design.

1 Claim, 6 Drawing Sheets(56)
